UNITED STATES PATENT OFFICE.

ARON BRILL, OF NEW YORK, N. Y.

DESIGN FOR A HAND BELL.

Application filed January 30, 1926. Serial No. 16,337. Term of patent 3½ years.

To all whom it may concern:

Be it known that I, ARON BRILL, a citizen of the United States, residing at the city of New York, county of Kings, and State of New York, have invented a new, original, and ornamental Design for a Hand Bell, of which the following is a specification, reference being had to the accompanying drawing, forming part thereof.

Figure 1 is a front elevation of the hand bell, and Fig. 2 is a side elevation of the same, showing my new design.

I claim:

The ornamental design for a hand bell, as shown.

In testimony whereof, I have signed my name to this specification this 25th day of January, 1926.

ARON BRILL.
